FRED D. CALKINS AND ALFRED C. JOHNSON, OF SUNNYVALE, CALIFORNIA.

INTERNAL-COMBUSTION ENGINE.

1,079,742.

Specification of Letters Patent. Patented Nov. 25, 1913.

Application filed May 8, 1912. Serial No. 695,847.

To all whom it may concern:

Be it known that we, FRED D. CALKINS and ALFRED C. JOHNSON, citizens of the United States, and residents of Sunnyvale, in the county of Santa Clara, State of California, have invented a new and useful Improvement in Internal-Combustion Engines, of which the following is a specification.

Our invention is an improvement in internal combustion engines, and has for its object the provision in an engine of the character specified, of a rotating valve having a large wearing surface and separated from the explosion chamber in order to prevent heating and deposits of carbon, and wherein means is provided for automatically compensating for the wear on the valve.

In the present application the combination in an explosion engine of a cylinder having a sectional bearing chamber for inclosing the valve, one of the sections being connected to a shell inclosing the cylinder, and resilient means capable of adjustment pressing the cylinder and the other section toward the first-named section is not claimed broadly, this combination being claimed broadly in my copending application, Serial No. 677,655, filed Feb. 15, 1912.

In the drawings: Figures 1 and 2 are longitudinal vertical sections, at right angles to each other, of the improved engine, Fig. 1 being taken on the line 1—1 of Fig. 2, and Fig. 2 on the line 2—2 of Fig. 1; and Fig. 3 is a plan view of the valve.

The present embodiment of the invention comprises a cylinder 1, having a jacket 2 at its upper end and an explosion chamber 3 at the said end. A spark plug 4 is threaded into an opening in the cylinder wall at the explosion chamber, and a piston 5 is slideable in the cylinder.

The crank case 6 is arranged below the cylinder and is provided with bearings 7 for the crank shaft 8, and the crank 9 of the shaft is connected to the piston by a piston rod 10. The rod engages a transverse pin 11 in the piston at one end and is provided with a sectional bearing 12 for engaging the crank pin at the other.

A fly wheel or pulley 13 is secured to one end of shaft 8, and a sprocket wheel 14 is secured to the shaft adjacent to the fly wheel. The cylinder 1 is inclosed by a shell or casing 15 which is provided at its upper and lower ends with lateral flanges 16 and 17, respectively. The flange 17 seats on the

crank case 6, around an opening 18, in line with the cylinder, and in which the cylinder is slideable.

The flange 17 is secured to the crank casting by cap screws 19, and the cylinder 1 has an annular rib 20 near its lower end, which engages the inner surface of the shell to hold the cylinder in proper alinement. The jacket 2 at the upper end of the cylinder serves a like purpose for the upper end. The rib 20 also engages the crank case around the opening 18 to limit the movement of the cylinder toward the crank case.

The piston has the usual packing rings 21, and when the said piston is in its outermost or highest position it does not reach the end of the cylinder, that is, does not enter the explosion chamber. The cooling liquid for the jacket 2 enters the jacket through a nipple or port 22, which extends laterally from the outer wall of the cylinder through a slot 23 in the shell 15. The spark plug 4 extends through a similar slot 23a in the shell. This arrangement permits the cylinder to move with respect to the shell without interference with the circulation of the cooling liquid. The cylinder beyond the explosion chamber is enlarged annularly, as shown at 24, and the outer end is closed. The closed end is concave transversely to form the inner section 25 of a bearing or valve chamber for the cylindrical valve, to be described.

The outer section 26 of the valve bearing or chamber is provided with a lateral flange 27, seating on flange 16 of the shell, and bolts or screws 28 connect the flanges 16 and 27. The section 26 is hollow, the inner end being closed and concave transversely to form with the section 25 a cylindrical valve chamber or bearing.

The hollow portion of the section 26 is in communication with the jacket 2, which is continued into the enlargement 24, and the cooling liquid enters through port 22 and circulates around the explosion chamber and the upper end of the cylinder in which the piston moves, the enlargement 24 and the hollow portion of the outer section 26, and passes out through an outlet opening 29 in the outer end of the section 26.

The communication between the enlargement 24 and the outer section of the bearing or chamber is by way of pipes or elbows 30 and 31. The pipe or elbow 30 extends laterally outward from the enlargement 24

and then upward, while pipe or elbow 31 extends laterally outward from the section 26 and then downward in alinement with pipe 30.

5 The adjacent ends of the pipes or elbows are connected by means of a union or stuffing box 32 arranged to make a fluid-tight joint between the pipes, while permitting them to move toward and from each other. The 10 shell 15 is slotted at 33 to permit the passage of pipe or elbow 30 and to permit the pipe to move with respect to the shell.

The valve 35 before mentioned is cylindrical and rotates in the bearing or valve chamber, and one end thereof is extended beyond the bearing and is provided with a sprocket wheel 36. A chain 37 connects the wheel 36 with wheel 14, and the wheels are so proportioned that the valve rotates once to 20 each four complete rotations of the crank shaft. The closed end 38 of the explosion chamber or cylinder is provided with an opening or port 39, extending longitudinally of the valve, and the outer section 26 25 is provided with two ports or openings 40 and 40^a. The port 40 is the inlet port or intake for the engine, and the port 40^a is the outlet or exhaust port.

The valve 35 has two transverse diametrical passages 41 and 41^a arranged at an angle to each other, and arranged to connect port 39 with ports 40 and 40^a alternately and in succession twice during each rotation of the valve. The cylinder is capable of movement 35 toward the valve to compensate for wear on the valve or bearings, and is supported by a spring 42. The valve having a large bearing surface does not wear readily, and the wear is uniform, so that no grinding is ever 40 required. The valve is also separated from the explosion chamber so that it does not readily heat, and, moreover, is encircled and inclosed by a large amount of cooling liquid. The large capacity of the sections of the 45 chamber permits a very thorough cooling of the valve bearing and of the valve, and there will be no deposits of carbon on the valve. The circulation of the cooling liquid between the bearing sections is permitted, whatever 50 the position of the cylinder with respect to the valve. The ports 40 and 40^a increase in cross section from within outward, as shown in Fig. 1, and the said passages or ports open laterally. Their inner ends, 55 however, are in alinement with the port 39. The spring 42 presses the cylinder toward the valve, so that the connection is always fluid tight, and so that any wear on the valve or bearing sections is at once compensated for. The spring permits the cylinder to yield, but presses it normally toward the outer section of the bearing. The lower 60 end of the spring 42 seats on the inner end of a lever 43, pivoted at 44, in a slot 45 in the crank case. The outer end of the lever

is engaged by a set screw 46, threaded through a lug 47 on the crank case. The tension of the spring and the pressure on the cylinder may thus be varied. When there is wear on the valve or on the bearing, 70 the set screw may be turned down to move the cylinder toward the outer section of the bearing. The spring at all times holds the cylinder tightly against the valve. The valve is hollow as shown, the ends being closed at 49, and is provided with a central transverse partition or diaphragm 48. Each 75 passage 41 and 41^a thus communicates with the hollow of the valve on one side of the partition, and the passages are effectively 80 separated by the partition.

We claim:

1. An engine of the character specified, comprising a cylinder having an explosion chamber at one end and a water jacket at 85 the said end extending over the explosion chamber and the outer end of the cylinder, the cylinder being closed at the outer end of the explosion chamber, said cylinder being enlarged annularly beyond the closed end to form a chamber for cooling liquid 90 communicating with the jacket, the outer end of the said enlarged portion being concave transversely to form a bearing section, said cylinder having a transverse passage 95 or port leading from the explosion chamber to the said end, an outer hollow bearing section at the outer end of the cylinder and co-operating with the inner section to form a cylindrical valve chamber, said outer section 100 having a pair of alined passages or ports registering with the port of the cylinder, said ports opening laterally of the outer bearing section, a pipe extending from each bearing section toward the other section, a 105 slidable connection between the pipes, a cylindrical valve in the bearing, said valve having transverse passages arranged at an angle to each other for alternately and successively connecting the ports of the outer 110 section to the port of the cylinder, a crank case at the opposite end of the cylinder, a shell inclosing the cylinder, said shell being secured at one end to the crank case and at the other to the outer section, said cylinder 115 being movable in the shell, the jacket of the cylinder having an inlet nipple extending laterally therefrom, a spark plug connected to the cylinder at the explosion chamber, the shell being slotted at the nipple and 120 the spark plug, the outer section of the bearing having an outlet for the cooling liquid, a piston in the cylinder, a connection between the piston and the valve for rotating said valve, and springs pressing the cylinder 125 toward the valve.

2. An engine of the character specified, comprising a cylinder having an explosion chamber at one end and having a transverse bearing section at the said end beyond the 130

explosion chamber, a crank case at the opposite end of the cylinder, a shell inclosing the cylinder and secured to the crank case, an outer bearing section secured to the other 5 end of the shell and coöperating with the section of the cylinder to form a cylindrical bearing, a valve in the bearing, a piston in the cylinder, a connection between the valve and the piston for rotating the valve, 10 said cylinder having a water jacket, and the bearing sections being hollow, the hollow of the inner section connecting with the jacket of the cylinder, a pipe leading from the hollow of each section toward the other 15 section, a slidale connection between the pipes, and springs between the crank case and the cylinder.

3. In an explosion engine, a cylinder provided at one end with a transverse bearing 20 section, an outer bearing section coöperating with the section of the cylinder, a crank case at the opposite end of the cylinder, a shell inclosing the cylinder and connected at one end to the crank case and at the other to the 25 outer bearing section, said bearing sections being chambered, and an expansible and

contractible connection between the chambers, the cylinder being jacketed, the jacket communicating with the chamber of the inner section, said cylinder having an inlet 30 nipple and a spark plug, the shell being slotted to permit the passage of the nipple and plug, the chamber of the outer section having an outlet, and springs between the crank case and the cylinder. 35

4. In an explosion engine, a cylinder provided at one end with a transverse bearing section, an outer bearing section coöperating with the section of the cylinder, a crank case at the opposite end of the cylinder, a shell 40 inclosing the cylinder and connected at one end to the crank case and at the other to the outer bearing section, said bearing sections being chambered, and an expansible and contractible connection between the chambers. 45
